CLAIM

The ornamental design for a handgrip for cleaning tool handles, as shown and described.

DESCRIPTION

FIG. 1 is a front isometric view of the present invention.

FIG. 2 is a rear isometric view of the present invention.

FIG. 3 is a full frontal isometric view of the present invention.

FIG. 4 is another rear isometric view of the present invention.

FIG. 5 is an elevation view of the present invention.

FIG. 6 is the opposite elevation view of the present invention.

FIG. 7 is a front view of the present invention.

FIG. 8 is a rear view of the present invention.

FIG. 9 is a top view of the present invention; and,

FIG. 10 is a bottom view of the present invention.

The broken lines in FIGS. 1 and 2 showing a section of a handle are included for the purpose of illustrating environment and form no part of the claimed design.
